UNITED STATES PATENT OFFICE.

CHARLES FABRIZIO AND ERNEST FORMICHELLA, OF ROME, NEW YORK.

VENDING MACHINE.

Application filed July 25, 1924. Serial No. 728,174.

To all whom it may concern:

Be it known that we, CHARLES FABRIZIO and ERNEST FORMICHELLA, citizens of the United States, and residents of Rome, county of Oneida, and State of New York, have invented certain new and useful Improvements in Vending Machines, of which the following is a specification.

This invention relates to vending machines for dispensing paper articles.

The object of this invention is to provide a vending machine for dispensing sanitary toilet seat covers, such as disclosed in our copending application, filed July 25, 1924, Serial No. 728,175. A further object is to provide a coin operating device in which coins of various denominations may be utilized for operating this machine. Compactness of form, accessibility, simplicity and durability are among the objects of this invention.

This invention resides principally in the particular combination and arrangement of parts as hereinafter fully described and claimed; reference being made to the accompanying drawing, forming a part hereof, and in which similar numerals refer to similar parts throughout the several views.

Fig. 1, represents an exterior view of the device forming the subject matter of this invention.

Fig. 2, is a front elevation of the mechanism contained within the cabinet represented in Fig. 1.

Fig. 3, is a side elevation of Fig. 2, the coin operating device being represented in sectional view taken on line 3—3 of Fig. 4.

Fig. 4, is a front elevation of a portion of Fig. 3, and is presented particularly to show the detail construction of the coin operating device. In this figure the front plate 7 of Fig. 3 is not included.

Fig. 5, is an elevation of the rear side of the coin operating device.

Fig. 6, is a detail drawing of the latching mechanism for the drum 8 of Fig. 3; this is a sectional view taken on line 6—6 of Fig. 3.

Describing this device in detail, 9 is the cabinet or outer casing which contains the mechanism shown in Figs. 2 and 3, the same being provided with a door 10 through which said mechanism may be removed for repairs, etc., or for replenishing the cabinet with a new stock of paper articles. The internal mechanism consists of two side frames 11 and 12 which are joined together through

the cross members 14, 15, 16 and 17. The brackets 18 and 19 form part of the side frames 11 and 12, respectively, and are adapted to carry free to rotate, the spindle 20. The feeding drum 8 is mounted in a manner free to rotate within suitable bearings 21 and 22, and the surface thereof is corrugated as shown at 23. A smaller drum 24 is also mounted free to rotate, and slide in the direction indicated by arrow 25, within the slots 26;—only one of these slots appear in the drawings, this being shown in the side frame 12 of Fig. 3, however the side frame 11 also has a slot of the same order.

The smaller drum 24 is also corrugated upon its surface, these corrugations are adapted to mesh with the corrugations 23 of the larger drum 8. The smaller drum 24 is normally held in mesh with the larger drum 8 through the tension springs 26. The connection between the spring 26 and the smaller drum 24 consists of a washer 28 which surrounds the shaft 29 as shown; the hole thereof being large enough to permit free rotating movement of the smaller drum. The small hole 30 is provided for receiving the end of the spring 26.

A bracket 31 is fixed to the side frame 12 and carries the pawl 32. The screw 33 forms a pivot for the pawl 32 and a spindle for carrying the torsion spring 34. The upper end 35 of the spring 34 bears against the side frame 12, and the opposite end 36 against the pin 36 which is carried by the pawl 32. Through this arrangement the pawl 32 is normally held in engagement in the notch 37 in the side of the drum 8. The drum 8 is provided with a boss 38 the purpose of which will be hereinafter fully explained.

The coin operating device consists of a casing 44, formed by the body portion 39 which is provided with channels 40 and 41, and the cover plate 42 which is fixed to the body portion 39 through screws 43. The cover plate is provided with a hole 47, and the main body portion with a tongue 45 which is bent to protrude slightly into the hole 44, as shown particularly in Fig. 3. Two bars 46 and 47 are fitted free to slide lengthwise in the channel 41 and are provided with V-shaped ends as shown at 48 and 49, respectively; these V-shaped ends being adapted to receive the coin 50 and hold the same central with respect to the

channel 41. A slot 51 is provided in the bar 47 to provide clearance for the tongue 45. The bars 46 and 47 are normally held in the uppermost position as shown, through the springs 52 and 53. The upper end of 52 being fixed to the side frame 12 through the pin 54, and the lower end to the bar 48 through the pin 55. The upper end of spring 53 is hooked to the pin 55, and the lower end is fixed to the bar 49 through the hook 56.

A slot 57 is formed in the body portion 39 through which the pin 55 protrudes, and this slot limits the upward movement of 15 the bar 46 when the pin 55 contacts at the upper end thereof. The bar 49 is limited in its upward movement when the tongue 25 contacts with the lower end of the slot 51. These stopping elements should be arranged 20 properly to permit sufficient space between the bars 46 and 47 to form a uniform continuation of the channel 40 as leading into the channel 41. The object being that when a coin is dropped into the channel 40, as 25 indicated by the arrow 58, the same will come to rest at the point shown and indicated by 50.

The articles of paper which are to be dispensed by this machine should be formed 30 into a roll as shown at 69, and should be of one continuous strip. This roll is carried by the spindle 20 and the end of the strip is led around the drum 8, over the drum 24, and over the cross member 61.

35 The operation of this device is as follows: A coin is dropped into the channel 40 from which it falls and rests as shown at 50. The bar 46 is moved downward by pressing on the end 71 in the direction indicated by arrow 72. The bar 47 is thereby moved downward through the medium of the coin 50. When the coin 50 reaches the hole 67, the tongue 45 forces the coin out from between the two bars 46 and 47, and 40 through the hole 67 from which it falls to the bottom of the cabinet. The spring 53 immediately pulls the bar 47 back to its original upward position; and the spring 52 pulls the bar 46 to its original position 45 when the pressure is released on the end 71. It is apparent that through the above described operation, the coin has been deposited within the cabinet 9, and the bar 47 has been given one downward and return 50 movement. This manipulation of the bar 47 causes the paper feeding mechanism to operate, however it is to be observed that downward movement of the bar 46 will not cause the bar 47 to move downward unless 55 a coin is interposed between these two bars as shown at 50, for in such case the pin 55 will contact with the lower end of the slot 57 before the end 48 of bar 46, will contact with the end 49 of bar 47, or at least before 60 enough movement is imparted to bar 47 to

cause any operation of the feeding mechanism.

Now downward movement of the bar 47 first releases the pawl 32 from the notch 37, this occurs through the beveled edge 73 70 which moves the pawl 32 in the direction indicated by arrow 74. Further downward movement of the bar 47 causes a slight rotation to the drum 8, through the end 75 thereof contacting with the boss 38. This 75 slight rotation of the drum 8 causes the slot 57 to move out of the proper location for engagement with the pawl 32, so that when the bar 47 returns to its original position the pawl 32 will not latch and lock the drum 8 80 against movement. This slight rotation of the drum 8 also causes the end of the paper to protrude a certain extent out of the slot 68 of the cabinet door.

Now after the coin has been dropped into 85 the coin operating device and the bar 46 has been pushed downward, the individual now grips the protruding end 59 of the paper and pulls on it until the drum 8 has made one complete revolution; this brings the slot 37 again into engagement with the pawl 32, and further rotating movement of the drum 8, or outward movement of the paper is arrested. The paper should now be torn off 90 over the edge 60 of the cross member 61. 95 It is preferable that the paper be perforated at this point to facilitate the tearing operation.

From the foregoing description it is apparent that with one coin this mechanism 100 may be manipulated to dispense one paper article of a certain length, this length being equal to the circumference of the drum 8; and that coins of various denominations 105 may be utilized, providing of course that the stopping elements for the bars 46 and 47, as heretofore described, are arranged to permit sufficient opening between said bars to receive the largest size coin which it is desired to use; and that notch 37 is made small 110 enough so that the pawl 32 will be held out of engagement therewith after the slight movement which will occur through the use of the smallest coin it is desired to use.

Having thus described our invention, 115 what we claim and desire to secure by Letters Patent is as follows:—

1. In a paper vending machine, the combination with a paper feeding drum, of a pawl arranged to lock said drum against 120 rotation, and a slidable bar having a beveled edge, said bar being arranged to partially rotate said drum through lengthwise movement thereof, and said beveled edge being arranged to engage said pawl and release the same from said drum before said rotating movement thereof is commenced.

2. In a paper vending machine, the combination with a paper feeding drum having a slot in the side thereof, of a boss on the 130

side of said drum, a slidable bar arranged to contact with said boss and effect a partial rotation of said drum through lengthwise movement thereof, a beveled edge on said slidable bar, a pawl arranged to normally engage said slot and become disengaged through the action of said beveled edge when said bar is moved lengthwise for effecting said partial rotation of the drum, and a coin operation device arranged to transmit sliding movement to said slidable bar through the medium of a coin.

3. In a coin operating device, the combination with a casing arranged to receive a coin and guide the same through gravitation to rest at a certain fixed point, of a slidable bar carried by said casing the end thereof supporting said coin at said certain fixed point, a second slidable bar carried by said casing above said coin when at rest, a spring normally pulling both of said bars together, and a second spring which normally holds the second said bar in its uppermost position.

4. In a coin operating device, the combination of a casing adapted to receive a coin and guide the same through gravitation to rest at a certain fixed point, and a hole in said casing large enough for said coin to pass through, and situated at a point below that at which said coin comes to rest, a slid- 25 able bar carried by said casing the end thereof supporting said coin at said certain fixed point, a second slidable bar carried by said casing above said coin when at rest, a tongue 30 carried by said casing and protruding into said hole, said tongue also serving as a stop to limit upward movement of the first said bar, stops to limit the movement of the second said bar in opposite directions, a spring 35 normally pulling both of said bars together, and a second spring which normally holds the second said bar in its uppermost position.

In testimony whereof, we affix our signatures.

CHARLES FABRIZIO.
ERNEST FORMICHELLA.
